(57) **CLAIM**

The ornamental design for a public lighting fixture, as shown and described.

DESCRIPTION

FIGURE 1.1 is a front elevation view of a public lighting fixture showing our new design;

FIGURE 1.2 is a right side elevation view thereof;

FIGURE 1.3 is a left side elevation view thereof;

FIGURE 1.4 is a perspective view thereof;

FIGURE 1.5 is a rear elevation view thereof;

FIGURE 1.6 is a bottom plan view thereof; and

FIGURE 1.7 is a top plan view thereof.

The broken lines in the drawings show portions of the public lighting fixture which form no part of the claimed design.

1 Claim, 7 Drawing Sheets
